[57] CLAIM

The ornamental design for a disposable absorbent article core, as shown and described.

DESCRIPTION

The FIGURE is a top plan view of a disposable absorbent article core, embodying my new design, with the bottom plan view being a mirror image.

The side and end elevational views are plain and unornamented, and the surfaces not shown form no part of the claimed invention.

The broken lines shown in the figures are for illustrative purposes only and form no part of the claimed invention.
